CASSETTE DISPLAY RACK

Michael D. Cockcroft, Larchmont, N.Y., assignor to Mar-Line Displays Inc., Port Chester, N.Y.

Filed Aug. 14, 1974, Ser. No. 497,236

Term of patent 14 years

Int. Cl. D6—04; D20—02

U.S. Cl. D6—172

Fig. 1

Fig. 2

Fig 3

Fig 5

FIG. 1 is a front perspective view of a cassette display rack showing my new design;

FIG. 2 is a rear perspective view thereof;

FIG. 3 is a top plan view thereof;

FIG. 4 is a front elevational view thereof; and

FIG. 5 is a perspective view thereof in the open position, the cassettes being shown in broken lines are for illustrative purposes only.

I claim:

The ornamental design for a cassette display rack, substantially as shown and described.
